UNITED STATES PATENT OFFICE.

GEORGE A. JONES, OF LYNN, MASSACHUSETTS, ASSIGNOR TO SHOE PRODUCTS, INC., OF LYNN, MASSACHUSETTS, A CORPORATION OF MASSACHUSETTS.

SHOE.

Application filed January 29, 1927. Serial No. 184,463.

The invention to be hereinafter described relates to shoes, and more particularly to a shoe which is specially manufactured so that heel and metatarsal arch supporting cushions 5 may be easily applied thereto.

Heretofore various devices have been applied to shoes for supporting the metatarsal arch of the foot, but so far as I am aware they have been expensive, difficult to apply, 10 and unsatisfactory. One of the purposes of the present invention, therefore, is to provide a shoe which is of usual construction with the exception of a simple unobjectionable change therein which enables heel and 15 metatarsal arch supporting cushions or either of them to be quickly and easily applied to the shoe.

The character of the invention may be best understood by reference to the following 20 description of good forms thereof, shown in the accompanying drawings, and the process of manufacturing the same.

In the drawing:

Fig. 1 is a perspective view of an insole 25 having cushion locating and holding holes therein, and shows the slugs removed in punching the holes;

Fig. 2 is a longitudinal section through a 30 portion of a man's shoe embodying the invention;

Fig. 3 is a bottom view of the heel cushion;

Fig. 4 is a bottom view of the metatarsal arch supporting cushion;

Fig. 5 is a longitudinal section through a 35 portion of the shoe and showing the heel and metatarsal arch supporting cushions applied to the insole after removal of the slugs from the holes therein;

Fig. 6 is a longitudinal section through a 40 portion of a lady's turned shoe embodying the invention;

Figs. 7 and 8 are respectively perspective 45 views of a shank and a fore part filler; and

Fig. 9 is a vertical section through a portion of the shoe shown in Fig. 6 and showing the heel and metatarsal arch supporting 50 cushions applied to the shank and fore part filler respectively after removal of the slugs from the holes therein.

Referring to the drawings, 1 (Fig. 1) designates an insole having a hole 3 punched in the heel portion of the insole and a hole 5 punched in the ball portion of the insole, said holes being of general oval form and 55 produced by punching out slugs 7 and 9

from the insole. These slugs are restored to or left in the holes in the insole, and may be held removably therein by webs 11 and 13 of cloth or paper and having areas larger than the slugs and secured to the upper and lower 60 surfaces of the insole by a suitable adhesive.

The insole described above may be built into a shoe in the process of manufacturing the same. In this process the upper 15, counter 17 and insole may be lasted in the 65 usual manner, and then the outsole may be applied. The hole in the heel portion of the insole is so located and of a size such that in punching the same it is directly above the cavity formed by the inturned margins 19 70 of the upper, counter and lining which are between the insole and the outsole. The hole in the ball portion of the insole is of an area and location such that it is in away from the inseam of the shoe. Thus the making of 75 these holes in the insole does not have any destructive effect upon or weaken the shoe.

The heel cushion may be substantially the same as that disclosed in my copending applications Serial Nos. 156,927 and 156,928, 80 both filed December 24, 1926. It is made of high grade rubber and comprises a diaphragm 21 (Fig. 3) having a collar 23 projecting down from the bottom thereof and of oval shape and appropriate size to fit into the hole 3 in the insole. The diaphragm is substantially larger than the hole and has a marginal portion which rests upon the upper 85 surface of the insole surrounding the hole. The construction of this diaphragm is such that when its collar is in the hole in the insole and the wearer of the shoe is walking, the diaphragm may flex up and down with pulsatile action, and will conform to the shape 90 of the base of the heel of the wearer of the shoe. The oval shape of the hole and the collar of the cushion will prevent the diaphragm from turning out of its normal proper position. Also the collar in the hole will prevent any shifting of the diaphragm 100 longitudinally or transversely of the insole.

The metatarsal arch supporting cushion may be substantially the same as disclosed in said application Serial No. 156,927. It is made of high grade rubber and comprises 105 a diaphragm 25 (Fig. 4) having a collar 27 projecting down from the bottom thereof, said collar being of oval form and of proper size to fit into the hole 5 in the ball portion of the insole. Projecting up from the dia-

phragm is a protuberance 29 (Fig. 5) which is suitably formed to furnish the proper support for the metatarsal arch of the foot. The diaphragm has a margin of substantial area which rests upon the upper surface of the insole. When the wearer is walking, the diaphragm and its protuberance are adapted to flex up and down with pulsatile action which will operate desirably to exercise and strengthen muscles of the foot and restore them to normal healthy condition, so that they will properly support the metatarsal arch of the foot.

The oval shape of the collar 23 of the arch supporting cushion and the oval shape of the hole 5 in the insole will prevent dislocation of the cushion from its proper position. It cannot shift longitudinally or transversely of the insole, and it cannot turn.

By my invention a shoe is provided of usual construction with the exception that the slugs are punched from the insole and left and secured therein so that to outward appearances the shoe is not different from the ordinary shoe. Shoes thus manufactured and supplied to retailers will be in readiness to receive the heel and metatarsal arch supporting cushions if a customer so desires. In applying these cushions it is merely necessary to remove the slugs from the holes in the insole, present the heel and metatarsal arch supporting cushions to the insole and insert their collars into the holes. These are simple operations quickly and easily accomplished. The hole is so located in the ball portion of the insole that if a person is fitted with a shoe of correct size, the metatarsal arch supporting cushion will be properly located to furnish the desired support for the arch.

A shoe provided with these cushions can be worn as an ordinary shoe, since they do not project into and occupy the space originally designed to receive the foot.

Goodyear welt, McKay, turned shoes and other types of shoes may be prepared to embody the present invention, in order that they may be adapted to receive the cushions described.

Referring now more particularly to Figs. 6 to 9, a lady's turned shoe is shown therein and comprises the upper 31, sole 33, heel 35, shank 37 and the fore part filler 39. The shank and the fore part filler have mating

feathered ends 41 and 43 which may be secured together by a staple. The hole 45 is made in the shank to receive the heel cushion, and the hole 47 is made in the fore part filler to receive the metatarsal arch supporting cushion. The shank and the fore part filler preferably have the holes punched therein before they are built into the shoe. The slugs 49 and 51 which are punched out in producing the shank hole and fore part filler hole, are left in their holes and are removably held therein by webs 53 and 55 of cloth or paper and having areas larger than the slugs and secured to the upper and lower surfaces of the shank and filler by suitable adhesive.

The cushions for application to the shank and the fore part filler may be similar to those described for the man's shoe, with the exception that the heel cushion necessarily would be made smaller and preferably its collar is of the same size as the collar of the metatarsal arch cushion. The holes 45 and 47 for receiving the collars preferably are made the same size.

If a lady's shoe is constructed with a full length filler, it would be similar to the insole shown in Fig. 1, but shaped appropriately for a lady's shoe.

The term "insole" employed in the claims is also to be regarded as generic to a full length filler and to a shank and fore part filler.

It will be understood that the invention is not limited to the specific process set forth herein and that various deviations may be made therefrom without departing from the spirit and scope of the appended claims.

I claim:

1. The process of preparing a shoe insole for receiving heel and metatarsal arch supporting cushions, which consist in punching slugs from an insole to form holes in the heel and ball portions of the insole, and leaving the slugs in the insole, that the slugs may be removed at will from the insole when in a manufactured shoe.

2. The process of preparing a shoe insole for receiving heel and metatarsal arch supporting cushions, which consists in punching slugs from an insole to form holes in the heel and ball portions of the insole, leaving the slugs in the holes in the insole, and removably securing the slugs in the holes in the insole.

GEORGE A. JONES.
